UNITED STATES PATENT OFFICE.

HENRIK C. LIDEN, OF THIEF RIVER FALLS, MINNESOTA.

GRAIN CLEANER AND SEPARATOR.

1,053,410.

Specification of Letters Patent. Patented Feb. 18, 1913.

Application filed April 2, 1912. Serial No. 688,057.

To all whom it may concern:

Be it known that I, HENRIK C. LIDEN, a citizen of the United States, residing at Thief River Falls, in the county of Pennington and State of Minnesota, have invented certain new and useful Improvements in Grain Cleaners and Separators, of which the following is a specification, reference being had to the accompanying drawings.

10 This invention comprehends certain new and useful improvements in grain cleaning and separating devices, and the invention has for its primary object an improved device of this character which will be self-15 operating.

The invention also has for its object a separator and cleaner provided with spiral internal flanges which will by the weight of the grain and the inclination of the cylinder, 20 impart automatically a rotary movement to the latter and which will embody means whereby the lower or discharge end of the cylinder may be adjusted to different elevations so as to maintain the revoluble cylinder 25 at the desired inclination.

The invention has for a further object a grain separating and cleaning device, the parts of which will be easy to manufacture and capable of being easily assembled, which 30 will be durable and not liable to get out of order and also efficient in operation. And the invention also aims to generally improve devices of this class and to render them more useful and commercially desirable.

35 With these and other objects in view, as will more fully appear as the description proceeds, the invention consists in certain constructions, arrangements and combinations of the parts that I shall hereinafter 40 fully describe and claim.

For a full understanding of the invention, reference is to be had to the following description and accompanying drawings in which,

45 Figure 1 is a side elevation of my improved grain separator and cleaner. Fig. 2 is a longitudinal sectional view thereof, the cylinder being shown in horizontal position in order to save space on the sheet. Fig. 50 3 is a sectional view on the line 3—3, of Fig. 1. Fig. 4 is a detail view of the receiving end of cylinder, and, Fig. 5 is a transverse sectional view on the line 5—5, of Fig. 2.

55 Corresponding and like parts are referred to in the following description and design-

nated in the accompanying drawings by like reference characters.

Referring to the drawings, the numeral 1 designates, as a whole, the frame-work of my improved grain separator and cleaner, the same being of any desired construction or design, so long as it will support the operating parts and being preferably higher at one end than the other, in view of the fact that the revoluble cylinder will at all times be held in an inclined position.

At one end of the frame-work 1, a feed hopper 2 is supported in any desired way, said feed hopper being provided with a spout 3 designed to discharge the grain into one end of the revoluble cylinder 4. The cylinder 4 includes a main body portion 5 of any desired length and diameter, constructed of a plurality of longitudinally extending spaced bars 6 and any desired number of reinforcing hoops or bands 7 riveted or otherwise secured to the bars. The end hoop at the inlet or receiving end of the cylinder is secured to the arms of a spider 8, to which a shaft 9 is connected, said shaft being journaled in a bearing 10 formed on or secured to the upper end of a standard 11 supported by the higher end of the frame-work 1. Surrounding the spider 8 and projecting from the end hoop 7 of the main body portion of the cylinder 4, is a preferably tapered annular receiving spout 11', into which the discharge end of the spout 3 projects, whereby a continuous flow of grain may be maintained from the hopper 2 into the cylinder. The body portion 5 of the cylinder 4 also embodies, in addition to the frame-work which is composed of the longitudinal bars 6 and hoops 7, a screen 12 of relatively fine mesh secured to the bars, and within the screen and in engagement with the inner wall thereof, are any desired number of spirally disposed blades arranged in two sets, with the blades of one set alternating with the blades of the other set. One set of blades is designated 13 and the other set 14, the latter being shorter than the former. All of these blades are secured to the hoops and bands, the blades being secured at one end to the end hoop 7 at the receiving end of the cylinder, and being secured at their opposite ends to the bands and hoops at the junction of the same. Any desired fastening devices may be used in securing these spiral blades in place.

At the discharge end of the main body

portion 5 of the cylinder, there are any desired number of concentric and substantially cylindrical skirts, the same, in the present instance, being four in number and extending varying distances from the main body portion 5. In order to identify them these skirts are designated, respectively, 15, which is the smallest in diameter, 16, which is next to the smallest in diameter, 17, of somewhat larger diameter and 18, the largest of them all. The screen or wire mesh which is embodied in the main body portion 5 of the cylinder, extends from the inlet end of said body portion to the hoop 19 at the outer end of the outermost skirt 18 and is of relatively fine mesh. The screen 20 which is of slightly coarser mesh, extends from the hoop 21 to the hoop 22 at the outer end of the skirt 17, the screen 23 which is of still coarser or larger mesh, extends from the hoop 21 to the hoop 24 at the outer end of the skirt 16, and the screen 25 which extends from the hoop 21 to the outermost hoop 15, longitudinally considered, is still coarser. In order to hold the overlying hoops, just mentioned, in properly spaced relation to each other, the rivets which connect them together, are encircled by spacing thimbles 26. From as much of the description as has preceded in connection with the correlated views of the accompanying drawings, it will be understood that as the grain flows from the hopper 2 through the spout 3 into the upper and receiving end of the revoluble cylinder 4, it will, by its own weight acting against the spiral blades 13 and 14, cause said cylinder to rotate and the grain will be tumbled and at the same time flow downwardly, the finest grain flowing out from the discharge end of the skirt 18, the next finest grain, as to grade or size, flowing out from the discharge end of the skirt 17, the next finest grain flowing out from the discharge end of the skirt 16, and the trash finally flowing out from the end of the skirt 15. The discharge end of the cylinder is tapered inwardly from the hoop 21 to the extremity of the cylinder, as is clearly shown in Figs. 1 and 2 of the drawings. This construction retards the flow of the grain and trash and thereby allows the grain to be thoroughly separated from the trash before the trash is discharged over the end of the cylinder. In order to catch the grain of different sizes, I provide transversely extending and laterally inclined spouts designated 27, 28 and 29, said spouts being, respectively, mounted underneath the discharge ends of the skirts 18, 17 and 16, so that the grain will be conveyed laterally out of the machine and deposited into sacks or any other desired receptacles. In order to support these spouts, I provide uprights 30 which

are secured to the side sills of the framework intermediate of the ends thereof and that are formed with a plurality of apertures 31 in a vertically disposed series designed to receive bolts for connecting to said uprights, one end of spout supporting bars 32. The other ends of said spout supporting bars 32 are correspondingly connected to the end uprights 33 at the discharge end of the frame-work 1, said uprights being formed with a plurality of apertures 34, as shown, whereby the bolts which connect the bars to said uprights, may be shifted in order to vary the elevations of the spouts in accordance with the elevation of the cylinder.

The entire cylinder, as above indicated, is held to rotate about its longitudinal axis in an inclined position, the receiving end being higher than the discharging end. The rear or discharging end of the cylinder is supported to be vertically adjusted by the following instrumentalities: The hoop 15 has a spider 35 connected to it, said spider being provided with a shaft 36 which is mounted in a bearing block 37. The block 37 is formed with a transversely apertured ear 38, through which a bolt or pin 39 passes, said pin also passing through any desired pairs of apertures 40 that are formed in the curved side members 41 of a vertically disposed supporting bracket 42 secured to the rear upper and lower cross bars of the frame-work 1, as best illustrated in Fig. 1. The bearing block 37 is mounted between the members 41 and bears against inturned flanges 43 that are formed on the bracket, whereby both side and end bearings are provided for the block. Manifestly, by removing the pin 39, the block 37 may be shifted upwardly or downwardly and the pin 39 replaced, whereby to hold the lower end of the revoluble cylinder at different elevations, and consequently, the entire cylinder at different elevations.

As the operation of the device has been described in connection with the details of construction and relative arrangement of the different parts, no further description of the operation is deemed necessary.

While the accompanying drawings illustrate what I believe to be the preferred embodiment of my invention, it is to be understood that the invention is not limited thereto, but that various changes may be made in the construction, arrangement and proportions of the parts without departing from the scope of the invention, as defined in the appended claims.

What I claim is:—

1. In a separator and cleaner of the character described, including a supporting frame, a cylinder mounted in the frame, means carried by the frame for holding the lower end of the cylinder at different elevations.

tions, a plurality of screens secured to the discharge end of the cylinder, a plurality of spouts arranged between said screens, and means carried by the frame for adjusting 5 said spouts at different elevations independent of the cylinder, as and for the purpose described.

2. In a separator and cleaner of the character described, including a supporting 10 frame, a cylinder mounted in the frame, means carried by the frame for holding the lower end of the cylinder at different elevations, a plurality of screens mounted on said cylinder at the discharge end thereof, spaced 15 uprights mounted in said frame, each of said uprights being provided with a vertical series of openings therein, bars extending longitudinally of the frame between said uprights, a plurality of spaced parallel 20 spouts arranged transversely upon the upper edges of said bars and in alignment with the discharge ends of said screens and pins disposed in the opposite ends of said bars and adapted for engagement with the open-

ings in said uprights whereby said spouts 25 may be adjusted at different elevations independent of the cylinder.

3. In a separator and cleaner of the character described, including a supporting frame, a cylinder mounted in the frame, 30 means carried by the frame for holding the lower end of the cylinder at different elevations, a plurality of concentric skirts encircling the discharge end of the cylinder, uprights mounted upon said frame, bars 35 extending longitudinally of the frame and adjustably connected at their opposite ends to said uprights, and a plurality of spaced parallel spouts arranged transversely upon the upper edges of said bars and in alignment with the discharge ends of said concentric skirts, substantially as described. 40

In testimony whereof I hereunto affix my signature in the presence of two witnesses.
